FISH LURE

James D. Maxwell, P.O. Box 649,
Vancouver, Wash. 98660

Filed Nov. 3, 1975, Ser. No. 628,567

Term of patent 14 years

Int. Cl. D22—05

U.S. Cl. D22—29

FIG. 1

FIG. 2

FIG. 3

FIG. 4

FIG. 5

FIG. 1 is a front elevational view of a fish lure showing my new design, this view being taken on the line 1—1 of FIG. 3;

FIG. 2 is a rear elevational view taken on the line 2—2 of FIG. 3;

FIG. 3 is a top plan view taken on the line 3—3 of FIG. 1;

FIG. 4 is a bottom plan view taken on the line 4—4 of FIG. 1; and

FIG. 5 is a side elevational view taken on the line 5—5 of FIG. 4.

I claim:

The ornamental design for a fish lure, as shown.
